(57) **ABSTRACT**

Packaging for a patient interface comprises: a plurality of panels arranged to be folded inwardly to define a housing for the patient interface, the plurality of panels comprising a pair of opposed side panels and a pair of opposed end panels; and a panel-retaining structure that is arranged to prevent outward collapse of the panels such that the patient interface is held in a compressed state; wherein at least one of the panels comprises at least one patient interface retaining feature that is attachable to the patient interface; and wherein the panel-retaining structure is releasable to cause the patient interface in the compressed state to urge one or more of the panels outwardly, to thereby enable display of the patient interface in a substantially in-use configuration.

PACKAGING FOR A PATIENT INTERFACE

1 CROSS-REFERENCE TO RELATED APPLICATIONS

This application is the U.S. national phase of International Application No. PCT/SG2022/050455 filed Jun. 30, 2022, which designated the U.S. and claims the benefit of Singapore patent application Ser. No. 10/202,200444Y, filed Jan. 17, 2022 and Singapore patent application Ser. No. 10/202,107191X, filed Jun. 30, 2021, the entire contents of each of which are hereby incorporated herein by reference in their entirety.

2 BACKGROUND OF THE TECHNOLOGY

2.1 Field of the Technology

The present technology relates to one or more of the screening, diagnosis, monitoring, treatment, prevention and amelioration of respiratory-related disorders. The present technology also relates to medical devices or apparatus, and their use.

2.2 Description of the Related Art

2.2.1 Human Respiratory System and its Disorders

The respiratory system of the body facilitates gas exchange. The nose and mouth form the entrance to the airways of a patient.

The airways include a series of branching tubes, which become narrower, shorter and more numerous as they penetrate deeper into the lung. The prime function of the lung is gas exchange, allowing oxygen to move from the inhaled air into the venous blood and carbon dioxide to move in the opposite direction. The trachea divides into right and left main bronchi, which further divide eventually into terminal bronchioles. The bronchi make up the conducting airways, and do not take part in gas exchange. Further divisions of the airways lead to the respiratory bronchioles, and eventually to the alveoli. The alveolated region of the lung is where the gas exchange takes place, and is referred to as the respiratory zone. See "Respiratory Physiology", by John B. West, Lippincott Williams & Wilkins, 9th edition published 2012.

A range of respiratory disorders exist. Certain disorders may be characterised by particular events, e.g. apneas, hypopneas, and hyperpneas.

Examples of respiratory disorders include Obstructive Sleep Apnea (OSA), Cheyne-Stokes Respiration (CSR), respiratory insufficiency, Obesity Hyperventilation Syndrome (OHS), Chronic Obstructive Pulmonary Disease (COPD), Neuromuscular Disease (NMD) and Chest wall disorders.

A range of therapies have been used to treat or ameliorate such conditions. Furthermore, otherwise healthy individuals may take advantage of such therapies to prevent respiratory disorders from arising. However, these have a number of shortcomings.

2.2.2 Therapies

Various respiratory therapies, such as Continuous Positive Airway Pressure (CPAP) therapy, Non-invasive ventilation (NIV), Invasive ventilation (IV), and High Flow Therapy (HFT) have been used to treat one or more of the above respiratory disorders.

2.2.2.1 Respiratory Pressure Therapies

Respiratory pressure therapy is the application of a supply of air to an entrance to the airways at a controlled target

pressure that is nominally positive with respect to atmosphere throughout the patient's breathing cycle (in contrast to negative pressure therapies such as the tank ventilator or cuirass).

5 2.2.3 Respiratory Therapy Systems

These respiratory therapies may be provided by a respiratory therapy system or device. Such systems and devices may also be used to screen, diagnose, or monitor a condition without treating it.

10 A respiratory therapy system may comprise a Respiratory Pressure Therapy Device (RPT device), an air circuit, a humidifier, a patient interface, an oxygen source, and data management.

15 2.2.3.1 Patient Interface

A patient interface may be used to interface respiratory equipment to its wearer, for example by providing a flow of air to an entrance to the airways. The flow of air may be provided via a mask to the nose and/or mouth, a tube to the mouth or a tracheostomy tube to the trachea of a patient. 20 Depending upon the therapy to be applied, the patient interface may form a seal, e.g., with a region of the patient's face, to facilitate the delivery of gas at a pressure at sufficient variance with ambient pressure to effect therapy, e.g., at a positive pressure of about 10 cmH₂O relative to ambient pressure. For other forms of therapy, such as the delivery of oxygen, the patient interface may not include a seal sufficient to facilitate delivery to the airways of a supply of gas at a positive pressure of about 10 cmH₂O. For flow therapies 25 such as nasal HFT, the patient interface is configured to insufflate the nares but specifically to avoid a complete seal. One example of such a patient interface is a nasal cannula.

The design of a patient interface presents a number of challenges. The face has a complex three-dimensional 30 shape. The size and shape of noses and heads varies considerably between individuals. Since the head includes bone, cartilage and soft tissue, different regions of the face respond differently to mechanical forces. The jaw or mandible may move relative to other bones of the skull. The whole head 35 may move during the course of a period of respiratory therapy.

As a consequence of these challenges, some masks suffer from being one or more of obtrusive, aesthetically undesirable, costly, poorly fitting, difficult to use, and uncomfortable especially when worn for long periods of time or when 40 a patient is unfamiliar with a system. Wrongly sized masks can give rise to reduced compliance, reduced comfort and poorer patient outcomes. Masks designed solely for aviators, 45 masks designed as part of personal protection equipment (e.g. filter masks), SCUBA masks, or for the administration of anaesthetics may be tolerable for their original application, but nevertheless such masks may be undesirably uncomfortable to be worn for extended periods of time, e.g., several hours. This discomfort may lead to a reduction in 50 patient compliance with therapy. This is even more so if the mask is to be worn during sleep.

CPAP therapy is highly effective to treat certain respiratory disorders, provided patients comply with therapy. If a mask is uncomfortable, or difficult to use a patient may not 55 comply with therapy. Since it is often recommended that a patient regularly wash their mask, if a mask is difficult to clean (e.g., difficult to assemble or disassemble), patients may not clean their mask and this may impact on patient compliance.

60 2.2.3.1.1 Seal-Forming Structure

Patient interfaces may include a seal-forming structure. Since it is in direct contact with the patient's face, the shape

and configuration of the seal-forming structure can have a direct impact the effectiveness and comfort of the patient interface.

A patient interface may be partly characterised according to the design intent of where the seal-forming structure is to engage with the face in use. In one form of patient interface, a seal-forming structure may comprise a first sub-portion to form a seal around the left naris and a second sub-portion to form a seal around the right naris. In one form of patient interface, a seal-forming structure may comprise a single element that surrounds both nares in use. Such single element may be designed to for example overlay an upper lip region and a nasal bridge region of a face. In one form of patient interface a seal-forming structure may comprise an element that surrounds a mouth region in use, e.g. by forming a seal on a lower lip region of a face. In one form of patient interface, a seal-forming structure may comprise a single element that surrounds both nares and a mouth region in use. These different types of patient interfaces may be known by a variety of names by their manufacturer including nasal masks, full-face masks, nasal pillows, nasal puffs and oro-nasal masks.

A seal-forming structure that may be effective in one region of a patient's face may be inappropriate in another region, e.g. because of the different shape, structure, variability and sensitivity regions of the patient's face. For example, a seal on swimming goggles that overlays a patient's forehead may not be appropriate to use on a patient's nose.

Certain seal-forming structures may be designed for mass manufacture such that one design fit and be comfortable and effective for a wide range of different face shapes and sizes. To the extent to which there is a mismatch between the shape of the patient's face, and the seal-forming structure of the mass-manufactured patient interface, one or both must adapt in order for a seal to form.

One type of seal-forming structure extends around the periphery of the patient interface, and is intended to seal against the patient's face when force is applied to the patient interface with the seal-forming structure in confronting engagement with the patient's face. The seal-forming structure may include an air or fluid filled cushion, or a moulded or formed surface of a resilient seal element made of an elastomer such as a rubber. With this type of seal-forming structure, if the fit is not adequate, there will be gaps between the seal-forming structure and the face, and additional force will be required to force the patient interface against the face in order to achieve a seal.

Another type of seal-forming structure incorporates a flap seal of thin material positioned about the periphery of the mask so as to provide a self-sealing action against the face of the patient when positive pressure is applied within the mask. Like the previous style of seal forming portion, if the match between the face and the mask is not good, additional force may be required to achieve a seal, or the mask may leak. Furthermore, if the shape of the seal-forming structure does not match that of the patient, it may crease or buckle in use, giving rise to leaks.

Another type of seal-forming structure may comprise a friction-fit element, e.g. for insertion into a naris, however some patients find these uncomfortable.

Another form of seal-forming structure may use adhesive to achieve a seal. Some patients may find it inconvenient to constantly apply and remove an adhesive to their face.

A range of patient interface seal-forming structure technologies are disclosed in the following patent applications, assigned to ResMed Limited: WO 1998/004,310; WO 2006/074,513; WO 2010/135,785.

5 One form of nasal pillow is found in the Adam Circuit manufactured by Puritan Bennett. Another nasal pillow, or nasal puff is the subject of U.S. Pat. No. 4,782,832 (Trimble et al.), assigned to Puritan-Bennett Corporation.

10 ResMed Limited has manufactured the following products that incorporate nasal pillows: SWIFT™ nasal pillows mask, SWIFT™ II nasal pillows mask, SWIFT™ LT nasal pillows mask, SWIFT™ FX nasal pillows mask and MIRAGE LIBERTY™ full-face mask. The following patent applications, assigned to ResMed Limited, describe 15 examples of nasal pillows masks: International Patent Application WO2004/073,778 (describing amongst other things aspects of the ResMed Limited SWIFT™ nasal pillows), US Patent Application 2009/0044808 (describing amongst other 20 things aspects of the ResMed Limited SWIFT™ LT nasal pillows); International Patent Applications WO 2005/063, 328 and WO 2006/130,903 (describing amongst other things aspects of the ResMed Limited MIRAGE LIBERTY™ 25 full-face mask); International Patent Application WO 2009/ 052,560 (describing amongst other things aspects of the ResMed Limited SWIFT™ FX nasal pillows).

2.2.3.1.2 Positioning and Stabilising

A seal-forming structure of a patient interface used for positive air pressure therapy is subject to the corresponding 30 force of the air pressure to disrupt a seal. Thus a variety of techniques have been used to position the seal-forming structure, and to maintain it in sealing relation with the appropriate portion of the face.

One technique is the use of adhesives. See for example 35 US Patent Application Publication No. US 2010/0000534. However, the use of adhesives may be uncomfortable for some.

Another technique is the use of one or more straps and/or 40 stabilising harnesses. Many such harnesses suffer from being one or more of ill-fitting, bulky, uncomfortable and awkward to use.

Positioning and stabilising structures for patient interfaces 45 may be somewhat complicated in design, due to (among other things) some of the challenges mentioned above. A user of a patient interface may have difficulty in understanding how to correctly set up and wear the patient interface without assistance from an expert such as a clinician. Accordingly, there remains a need for a way to facilitate setup and use of patient interfaces.

50 2.2.3.2 Respiratory Pressure Therapy (RPT) Device

A respiratory pressure therapy (RPT) device may be used individually or as part of a system to deliver one or more of a number of therapies described above, such as by operating the device to generate a flow of air for delivery to an 55 interface to the airways. The flow of air may be pressure-controlled (for respiratory pressure therapies) or flow-controlled (for flow therapies such as HFT). Thus RPT devices may also act as flow therapy devices. Examples of RPT devices include a CPAP device and a ventilator.

60 2.2.3.3 Air Circuit

An air circuit is a conduit or a tube constructed and arranged to allow, in use, a flow of air to travel between two components of a respiratory therapy system such as the RPT device and the patient interface. In some cases, there may be 65 separate limbs of the air circuit for inhalation and exhalation. In other cases, a single limb air circuit is used for both inhalation and exhalation.

3 BRIEF SUMMARY OF THE TECHNOLOGY

The present technology is directed towards providing medical devices used in the screening, diagnosis, monitoring, amelioration, treatment, or prevention of respiratory disorders having one or more of improved comfort, cost, efficacy, ease of use and manufacturability.

A first aspect of the present technology relates to apparatus used in the screening, diagnosis, monitoring, amelioration, treatment or prevention of a respiratory disorder.

Another aspect of the present technology relates to a patient interface for delivering pressurised breathable gas to a patient. The patient interface comprises a seal-forming structure for sealing around an entrance to the patient's airways. The patient interface also comprises a plenum chamber configured to receive a flow of pressurised breathable gas. The patient interface also comprises a positioning and stabilising structure configured to maintain the seal-forming structure in an operable position.

Another aspect of the present technology relates to methods used in the screening, diagnosis, monitoring, amelioration, treatment or prevention of a respiratory disorder.

An aspect of certain forms of the present technology is to provide methods and/or apparatus that improve the compliance of patients with respiratory therapy.

One form of the present technology comprises a packaging for a patient interface.

One form of the present technology comprises a foldable packaging with movable panels in order to form an opened and closed position.

One form of the present technology comprises panels of a housing including at least one retaining structure configured to retain a patient interface in a desired position.

One form of the present technology comprises a packaging having panels and a panel retaining structure. The panels are movable from an outwardly collapsed state to an in use state. The panel retaining structure selectively maintaining the position of the panels in the in use state.

In some forms, the panel retaining structure may be disposed on one of the panels. For example, the panel retaining structure may be a fastener (e.g., a magnet, hook and loop material, a mechanical fastener, etc.) on one panel that removably connects to a fastener on another panel.

One form of the present technology comprises a packaging for a patient interface comprising a plurality of panels arranged to be folded inwardly to define a housing for the patient interface, the plurality of panels comprising a pair of opposed side panels and a pair of opposed end panels, and a panel-retaining structure that is arranged to prevent outward collapse of the panels such that the patient interface is held in a compressed state; wherein at least one of the panels comprises at least one patient interface retaining feature that is attachable to the patient interface; and wherein the panel-retaining structure is releasable to cause the patient interface in the compressed state to urge one or more of the panels outwardly, to thereby enable display of the patient interface in a substantially in-use configuration.

Another aspect of one form of the present technology is the at least one patient interface retaining feature comprises one or more of: a tie; a clip; a press stud; a strap; a hook and loop fastener; a button; and a magnet.

Another aspect of one form of the present technology is when the at least one patient interface retaining feature comprises a magnet, one of the end panels comprises at least two patient interface retaining features arranged to be magnetically attractive to each other.

Another aspect of one form of the present technology is the at least one patient interface retaining feature comprises a magnet for attracting to a magnet on the patient interface.

Another form of the present technology comprises a packaging comprising a plurality of panels arranged to move from an open position to a closed position that at least partially forms a volume for receiving the patient interface, the plurality of panels comprising a pair of opposed side panels and a pair of opposed end panels, wherein each of the 10 plurality of panels are movable independently of the other panels of the plurality of panels; and a panel-retaining structure removably connected to at least one of the panels of the plurality of panels, the panel-retaining structure being arranged to prevent outward collapse of the panels in a connected position; at least one patient interface retaining 15 feature connected to at least one of the panels of the plurality of panels, the at least one patient interface retaining feature configured to removably connect to the patient interface and retain the patient interface in a desired position; and wherein 20 the plurality of panels are biased toward the open position and are configured to move toward the open position when the panel-retaining structure is released from the at least one panel of the plurality of panel.

In some forms, a) the at least one patient interface 25 retaining feature comprises one or more of: a tie; a clip; a press stud; a strap; a hook and loop fastener; a button; and a magnet; b) the at least one patient interface retaining feature comprises a plurality of patient interface retaining features; and/or c) one patient interface retaining feature of 30 the plurality of patient interface retaining features is connected to each panel of the plurality of panels.

In some forms, a) a pair of side flaps and an end flap extend from at least one end panel of the pair of opposed end panels; b) the pair of side flaps and the end flap are oriented 35 substantially perpendicularly to the at least one end panel in the open position and in the closed position; c) each side flap of the pair of side flaps contacts one side panel of the pair of opposed side panels in the closed position; d) the at least one end panel is a pair of end panels and each end panel of 40 the pair of end panels includes a pair of side flaps and an end flap; e) each side flap of the pair of side flaps of the pair of end panels contacts one side panel of the pair of opposed side panels in the closed position; f) the pair of side flaps of one of the least one end panel is spaced apart from the pair 45 of side flaps of the other of the at least one end panel; g) a sleeve removably positioned around an exterior surface of the at least one end panel; h) the sleeve is configured to selectively retain the at least one end panel in the closed position; and/or i) the sleeve is in contact with the end flap.

In some forms, a) a hook is connected to a top panel of the 50 extending from the at least one end panel; b) the hook is connected to the top panel as a cantilever structure; c) a bottom wall is configured to support the plurality of panels in an upright position; d) each panel of the plurality of panels 55 is connected to the bottom wall via a hinge; and/or e) each panel of the plurality of panels is configured to pivotably move relatively to the bottom wall.

In some forms, a packaging system may include a patient interface and the packaging of any one of the previous 60 forms.

Another form of the present technology comprises a storage system comprising a patient interface; and a packaging configured to selectively house the patient interface, the packaging comprising, a plurality of panels arranged to move from an open position to a closed position that at least 65 partially forms a volume for receiving the patient interface, the plurality of panels comprising a pair of opposed side

panels and a pair of opposed end panels, wherein each of the plurality of panels are movable independently of the other panels of the plurality of panels; at least one patient interface retaining feature connected to at least one of the panels of the plurality of panels, the at least one patient interface retaining feature configured to removably connect to the patient interface and retain the patient interface in a desired position, the at least one patient interface retaining feature comprising a male part and a female part configured to selectively connect to one another, wherein the patient interface retaining feature forming a loop when the male part and the female part are connected to one another, and wherein the loop is configured to wrap around a portion of the patient interface.

In some forms, a) the packaging further comprises a panel-retaining structure that is arranged to prevent outward collapse of the panels such that the patient interface is held in a compressed state; b) the panel-retaining structure comprises a lid having at least one flap arranged to engage an external surface of a first end panel of the pair of opposed end panels; c) the lid extends from, and/or comprises at least part of, a second end panel of the pair of opposed end panels; d) the lid has a hinge that is connected to, or is part of, the second end panel; and/or e) part of the second end panel forms a top wall of the lid.

In some forms, a) the panels are joined by a foldable web; b) the lid comprises first and second lid portions each comprising a pair of opposed side flaps arranged to engage with respective side panels; c) the panel-retaining structure comprises the opposed side flaps of the first and second lid portions; and/or d) each lid portion comprises a top wall extending transversely of its opposed side flaps and a respective one of the end panels.

In some forms, a) the at least one patient interface retaining feature comprises a strap; b) the strap is formed from a cut-out portion of a layer of material that is laminated to one of the panels; c) the strap includes a male part formed on one panel of the plurality of panels and a female part formed on another one of the plurality of panels adjacent to the one panel of the plurality of panels; d) the male part and the female part selectively form a mechanical connection between themselves in order to form the loop for retaining the patient interface; e) the male part includes an undercut selectively receivable within a groove of the female part; and/or f) the male part and the female part are selectively connected to one another using a magnetic force.

In some forms, a) the at least one patient interface retaining feature comprises a strap; b) the male part formed on either the strap or the at least one panel and the female part formed on the other of the strap or at least one panel; c) the male part and the female part comprises one or more of: a press stud; a hook and loop fastener; a button; and a magnet; d) one of the end panels comprises at least two patient interface retaining features arranged to attach to the patient interface on either side of a seal-forming structure of the patient interface, or at opposed ends of a posterior strap of a positioning and stabilising structure of the patient interface; and/or e) the at least one patient interface retaining feature comprises a magnet for attracting to a magnet on the patient interface.

Another aspect of one form of the present technology is a patient interface that is moulded or otherwise constructed with a perimeter shape which is complementary to that of an intended wearer.

An aspect of one form of the present technology is a method of manufacturing apparatus.

An aspect of certain forms of the present technology is a medical device that is easy to use, e.g. by a person who does not have medical training, by a person who has limited dexterity, vision or by a person with limited experience in using this type of medical device.

An aspect of one form of the present technology is a portable RPT device that may be carried by a person, e.g., around the home of the person.

An aspect of one form of the present technology is a patient interface that may be washed in a home of a patient, e.g., in soapy water, without requiring specialised cleaning equipment. An aspect of one form of the present technology is a humidifier tank that may be washed in a home of a patient, e.g., in soapy water, without requiring specialised cleaning equipment.

The methods, systems, devices and apparatus described may be implemented so as to improve the functionality of a processor, such as a processor of a specific purpose computer, respiratory monitor and/or a respiratory therapy apparatus. Moreover, the described methods, systems, devices and apparatus can provide improvements in the technological field of automated management, monitoring and/or treatment of respiratory conditions, including, for example, sleep disordered breathing.

Of course, portions of the aspects may form sub-aspects of the present technology. Also, various ones of the sub-aspects and/or aspects may be combined in various manners and also constitute additional aspects or sub-aspects of the present technology.

Other features of the technology will be apparent from consideration of the information contained in the following detailed description, abstract, drawings and claims.

4 BRIEF DESCRIPTION OF THE DRAWINGS

The present technology is illustrated by way of example, and not by way of limitation, in the figures of the accompanying drawings, in which like reference numerals refer to similar elements including:

4.1 Respiratory Therapy Systems

FIG. 1 shows a system including a patient **1000** wearing a patient interface **3000**, in the form of a nasal mask, receiving a supply of air at positive pressure from an RPT device **4000**. Air from the RPT device is humidified in a humidifier **5000**, and passes along an air circuit **4170** to the patient **1000**.

4.2 Patient Interface

FIG. 2 shows a patient interface in the form of a nasal mask in accordance with one form of the present technology.

FIG. 3A shows a side view of a patient interface in accordance with one form of the present technology.

FIG. 3B shows a close-up side perspective view of the patient interface of FIG. 3A.

FIG. 3C shows part of the patient interface of FIG. 3A in partially disassembled form, with a rigidizer of the patient interface exposed.

FIG. 3D shows the part of the patient interface with the rigidizer inserted into a strap.

4.3 Packaging for a Patient Interface

FIG. 4A shows packaging in an open configuration for a patient interface in accordance with one form of the present technology.

FIG. 4B shows the packaging with a patient interface as it is displayed when the packaging is opened.

FIG. 4C shows the opened packaging with patient interface retaining features.

FIG. 4D shows the opened packaging with patient interface retaining features attached to the patient interface.

FIG. 5A shows a top view of the packaging of FIGS. 4A to 4D at the start of an opening sequence.

FIG. 5B shows a top view of the packaging mid-way through the opening sequence.

FIG. 5C shows a top view of the packaging at the end of the opening sequence.

FIG. 6A shows packaging in an open configuration for a patient interface in accordance with another form of the present technology.

FIG. 6B shows the packaging of FIG. 6A with a patient interface as it is displayed when the packaging is opened.

FIG. 6C shows the opened packaging of FIG. 6A with patient interface retaining features.

FIG. 6D shows the opened packaging of FIG. 6A with patient interface retaining features attached to the patient interface.

FIG. 7A shows a top view of the packaging of FIGS. 6A to 6D at the start of an opening sequence.

FIG. 7B shows a top view of the packaging part-way through the opening sequence with a sleeve of the packaging partially removed.

FIG. 7C shows a top view of the packaging part-way through the opening sequence with the sleeve fully removed.

FIG. 7D shows a top view of the packaging at the end of the opening sequence.

FIG. 8A shows a top view of packaging with an example of patient interface retaining features.

FIG. 8B shows a top view of packaging with another example of patient interface retaining features.

FIG. 8C shows a top view of packaging with a further example of patient interface retaining features.

FIGS. 8D and 8E shows a top view of packaging with a yet further example of patient interface retaining features.

FIG. 8F is a close-up top perspective view of packaging with a yet further example of a patient interface retaining feature.

FIG. 8G shows a top view of packaging with a yet further example of patient interface retaining features.

FIG. 9A shows a front perspective view of packaging for a patient interface in accordance with an example of the present technology, in a closed configuration.

FIG. 9B shows a front perspective view of the packaging of FIG. 9A, partially opened.

FIG. 9C shows a front perspective view of the packaging of FIG. 9A, fully opened and without the patient interface.

FIG. 9D shows a patient interface retaining feature of the packaging of FIG. 9A.

5 DETAILED DESCRIPTION OF EXAMPLES OF THE TECHNOLOGY

Before the present technology is described in further detail, it is to be understood that the technology is not limited to the particular examples described herein, which may vary. It is also to be understood that the terminology used in this disclosure is for the purpose of describing only the particular examples discussed herein, and is not intended to be limiting.

The following description is provided in relation to various examples which may share one or more common characteristics and/or features. It is to be understood that one or more features of any one example may be combinable with one or more features of another example or other

examples. In addition, any single feature or combination of features in any of the examples may constitute a further example.

5.1 THERAPY

In one form, the present technology comprises a method for treating a respiratory disorder comprising applying positive pressure to the entrance of the airways of a patient 1000.

In certain examples of the present technology, a supply of air at positive pressure is provided to the nasal passages of the patient via one or both nares.

In certain examples of the present technology, mouth breathing is limited, restricted or prevented.

5.2 RESPIRATORY THERAPY SYSTEMS

In one form, the present technology comprises a respiratory therapy system for treating a respiratory disorder. The respiratory therapy system may comprise an RPT device 4000 for supplying a flow of air to the patient 1000 via an air circuit 4170 and a patient interface 3000.

5.3 PATIENT INTERFACE

A non-invasive patient interface 3000 in accordance with one aspect of the present technology comprises the following functional aspects: a seal-forming structure 3100, a plenum chamber 3200, a positioning and stabilising structure 3300, a vent 3400, one form of connection port 3600 for connection to air circuit 4170, and a forehead support 3700. In some forms a functional aspect may be provided by one or more physical components. In some forms, one physical component may provide one or more functional aspects. In some forms the seal-forming structure 3100 is arranged to surround an entrance to the airways of the patient so as to maintain positive pressure at the entrance(s) to the airways of the patient 1000. The sealed patient interface 3000 is therefore suitable for delivery of positive pressure therapy.

If a patient interface is unable to comfortably deliver a minimum level of positive pressure to the airways, the patient interface may be unsuitable for respiratory pressure therapy.

The patient interface 3000 in accordance with one form of the present technology is constructed and arranged to be able to provide a supply of air at a positive pressure of at least 6 cmH2O with respect to ambient.

The patient interface 3000 in accordance with one form of the present technology is constructed and arranged to be able to provide a supply of air at a positive pressure of at least 10 cmH2O with respect to ambient.

The patient interface 3000 in accordance with one form of the present technology is constructed and arranged to be able to provide a supply of air at a positive pressure of at least 20 cmH2O with respect to ambient.

5.3.1 Seal-Forming Structure

In one form of the present technology, a seal-forming structure 3100 provides a target seal-forming region, and may additionally provide a cushioning function. The target seal-forming region is a region on the seal-forming structure 3100 where sealing may occur. The region where sealing actually occurs—the actual sealing surface—may change within a given treatment session, from day to day, and from patient to patient, depending on a range of factors including for example, where the patient interface was placed on the face, tension in the positioning and stabilising structure and the shape of a patient's face.

5.3.1.1 Nasal Pillows

In one form the seal-forming structure of the non-invasive patient interface **3000** comprises a pair of nasal puffs, or nasal pillows, each nasal puff or nasal pillow being constructed and arranged to form a seal with a respective naris of the nose of a patient.

5.3.2 Plenum Chamber

The plenum chamber **3200** has a perimeter that is shaped to be complementary to the surface contour of the face of an average person in the region where a seal will form in use. In use, a marginal edge of the plenum chamber **3200** is positioned in close proximity to an adjacent surface of the face. Actual contact with the face is provided by the seal-forming structure **3100**. The seal-forming structure **3100** may extend in use about the entire perimeter of the plenum chamber **3200**. In some forms, the plenum chamber **3200** and the seal-forming structure **3100** are formed from a single homogeneous piece of material.

5.3.3 Positioning and Stabilising Structure

The seal-forming structure **3100** of the patient interface **3000** of the present technology may be held in sealing position in use by the positioning and stabilising structure **3300**.

In one form of the present technology, a positioning and stabilising structure **3300** is provided with a decoupling portion located between an anterior portion of the positioning and stabilising structure **3300**, and a posterior portion of the positioning and stabilising structure **3300**. The decoupling portion does not resist compression and may be, e.g. a flexible or floppy strap. The decoupling portion is constructed and arranged so that when the patient lies with their head on a pillow, the presence of the decoupling portion prevents a force on the posterior portion from being transmitted along the positioning and stabilising structure **3300** and disrupting the seal.

In one form of the present technology, a positioning and stabilising structure **3300** comprises a strap constructed from a laminate of a fabric patient-contacting layer, a foam inner layer and a fabric outer layer. In one form, the foam is porous to allow moisture, (e.g., sweat), to pass through the strap. In one form, the fabric outer layer comprises loop material to engage with a hook material portion.

In certain forms of the present technology, a positioning and stabilising structure **3300** comprises a strap that is extensible, e.g. resiliently extensible. For example the strap may be configured in use to be in tension, and to direct a force to draw a seal-forming structure into sealing contact with a portion of a patient's face. In an example the strap may be configured as a tie.

In one form of the present technology, the positioning and stabilising structure comprises a first tie (e.g. first tie **3304** in FIG. 3A and FIG. 3C), the first tie being constructed and arranged so that in use at least a portion of an inferior edge thereof passes superior to an otobasion superior of the patient's head and overlays a portion of a parietal bone without overlaying the occipital bone.

In one form of the present technology suitable for a nasal-only mask or for a full-face mask, the positioning and stabilising structure includes a second tie (e.g. second tie **3306** in FIG. 3A and FIG. 3C), the second tie being constructed and arranged so that in use at least a portion of a superior edge thereof passes inferior to an otobasion inferior of the patient's head and overlays or lies inferior to the occipital bone of the patient's head.

In one form of the present technology suitable for a nasal-only mask or for a full-face mask, the positioning and stabilising structure includes a third tie (e.g. strap connector

3308 in FIG. 3A and FIG. 3C) that is constructed and arranged to interconnect the first tie and the second tie to reduce a tendency of the first tie and the second tie to move apart from one another.

In certain forms of the present technology, a positioning and stabilising structure **3300** comprises a strap that is bendable and e.g. non-rigid. An advantage of this aspect is that the strap is more comfortable for a patient to lie upon while the patient is sleeping.

In certain forms of the present technology, a positioning and stabilising structure **3300** comprises a strap constructed to be breathable to allow moisture vapour to be transmitted through the strap.

One example of a strap **3302** is shown in FIGS. 3A-3D. The strap **3302** comprises a fabric outer layer **3314** that forms a sleeve for a rigidizer **3316**. A "rigidizer" means and includes any reinforcing element that increases the rigidity of another item and may include an object that increases rigidity in one or more axes. The rigidizer **3316** may be resiliently flexible along at least part of its length.

In some forms of the present technology, with reference to FIGS. 3A to 3D, the strap **3302** may be connected directly or indirectly to the plenum chamber **3200** via a concertina section **3322**. For example, the concertina section **3322** may extend directly from the plenum chamber **3200** itself, or may extend from a rigid outer shell **3320** that connects to a soft and/or resilient plenum chamber **3200**. The strap **3302** may be connected to the concertina section **3322** via an end **3310** of rigidizer **3316**, for example.

In some forms, the strap **3302** may comprise a tab **3309** comprising a connector **3307** for connecting the strap **3302** to the second tie **3306**. The connector **3307** may comprise a button or press stud, for example.

In some forms of the present technology, the positioning and stabilising structure **3300** may comprise a pair of straps **3302** that are connected by a crown tie **3303**. The crown tie **3303** may be adjustable in length for better fitting of the positioning and stabilising structure **3300** to the patient's head.

In some forms, each of the pair of straps **3302** may be connected to the first tie **3304** via a tab **3305**. The tab **3305** may include a loop that permits the first tie **3304** to be threaded through and removably connected in an adjustable manner to adjust the length of the strap **3304**.

In certain forms of the present technology, a system is provided comprising more than one positioning and stabilizing structure **3300**, each being configured to provide a retaining force to correspond to a different size and/or shape range. For example the system may comprise one form of positioning and stabilizing structure **3300** suitable for a large sized head, but not a small sized head, and another, suitable for a small sized head, but not a large sized head.

5.3.4 Vent

In one form, the patient interface **3000** includes a vent **3400** constructed and arranged to allow for the washout of exhaled gases, e.g. carbon dioxide.

The vent **3400** may be located in the plenum chamber **3200**. Alternatively, the vent **3400** is located in a decoupling structure, e.g., a swivel.

5.3.5 Decoupling Structure(s)

In one form the patient interface **3000** includes at least one decoupling structure, for example, a swivel or a ball and socket.

5.3.6 Connection Port

Connection port **3600** allows for connection to the air circuit **4170**.

5.3.7 Forehead Support

In one form, the patient interface **3000** includes a forehead support **3700**.

5.3.8 Ports

In one form of the present technology, a patient interface **3000** includes one or more ports that allow access to the volume within the plenum chamber **3200**. In one form this allows a clinician to supply supplementary oxygen. In one form, this allows for the direct measurement of a property of gases within the plenum chamber **3200**, such as the pressure.

5.4 PACKAGING FOR A PATIENT INTERFACE

One form of the present technology comprises packaging for a patient interface. The patient interface may be a patient interface **3000** of the type depicted in FIG. 2 and FIGS. 3A-3D, though it will be appreciated that the packaging may be used with many other types of patient interface with suitable modification.

In one form, as shown in FIGS. 4A to 4D, packaging **6000** for a patient interface **3000** comprises a plurality of panels **6004a**, **6004b**, **6006**. The plurality of panels is arranged to be folded inwardly to define a housing for the patient interface **3000**.

In this example, the plurality of panels comprises a first end panel **6004a** comprising a first panel portion **6034** and a second panel portion **6036** that are joined at a fold **6040**. First panel portion **6034** may be folded inwardly (i.e., in the direction of second panel portion **6036**) about fold **6040** to a generally upright position to form a first end wall of the housing for the patient interface. Second panel portion **6036** thus forms a bottom wall of the housing. In some forms, the upright position may be where the first panel portion **6034** is substantially perpendicular to the second panel portion **6036**.

The plurality of panels also comprises a second end panel **6004b** that comprises a first panel portion **6021** and a second panel portion **6022** that are joined at a fold **6030** at one end of the first panel portion **6021**. The first panel portion **6021** is joined at its other end to the first end panel **6004a** via another fold **6032**. The first panel portion **6021** is inwardly foldable (i.e., in the direction of first end panel **6004a**) about the fold **6032** to a generally upright position to form a second end wall of the housing for the patient interface **3000**. In some forms, the upright position may be where the first panel portion **6021** is substantially perpendicular to the second panel portion **6036**. In this position, the first panel portion **6034** and the first panel portion **6021** may be substantially parallel to one another.

The plurality of panels further comprises a pair of opposed side panels **6006**. Each side panel **6006** may be connected to first end panel **6004a** via a fold **6007**, e.g. at the second panel portion **6036** of the first end panel **6004a**. Each side panel **6006** is inwardly foldable (i.e., in the direction of the first end panel **6004a**) about its respective fold **6007** to a generally upright position to form a side wall of the housing for the patient interface **3000**. In some forms, the upright position may be where at least one of the side panels **6006** is substantially perpendicular to the second panel portion **6036**. In this position, the side panels **6006** may be substantially parallel to one another. However, other examples may include one or more side panels **6006** inclined with respect to the second panel portion **6036** and/or the other side panels **6006** in the upright position.

The second panel portion **6022** of second end panel **6004b**, as well as being foldable about the fold **6032**, is also inwardly foldable (i.e., in the direction of the first panel

portion **6021**) about fold **6030** such that the second panel portion **6022** forms a top wall of the housing for the patient interface **3000**. The top wall **6022** thus forms part of a lid **6020** for the packaging **6000**.

5 The lid **6020** may further comprise an end flap **6024** extending generally perpendicular to the top wall **6022**. When the first end panel **6004a** is folded inwardly about fold line **6040**, and the second end panel **6004b** is folded inwardly about the fold lines **6032** and **6030**, the end flap **6024** of the lid **6020** may engage with an external surface of the first panel portion **6034** of the first end panel **6004a**. The end flap **6024** acts as a panel-retaining structure to prevent outward collapse of the first end panel **6004a** (specifically, in this case, the first panel portion **6034** of the first end panel **6004a**).

10 In some forms, the end flap **6024** may be retained in its illustrated position in FIG. 4A relative to the top wall **6022**. This may allow the end flap **6024** to act as a backstop and not move (e.g., pivot) when contacted by the first end panel portion **6034**, which enables the end flap **6024** to act as the panel-retaining structure.

15 As shown, the end flap **6024** has a height that is substantially equal to a height of the end wall defined by the first panel portion **6034** of the first end panel **6004a**. However, it will be appreciated that in some forms, the flap **6024** may be smaller than this and still act as a panel-retaining structure, or part thereof.

20 The lid **6020** may also comprise a pair of opposed side flaps **6026** that extend mutually perpendicularly to the top wall **6022** and the end flap **6024**. The side flaps **6026** may be connected to both the top wall **6022** and the end flap **6024**. Accordingly, when side panels **6006**, first end panel **6004a** and second end panel **6004b** are all folded inwardly, each side flap **6026** of the lid **6020** may be arranged to engage 25 with respective external surfaces of the side panels **6006** in their upright position, and thus act as part of a panel-retaining structure that also comprises the end flap **6024**. The side flaps **6026** may, but need not, each have a height that is substantially equal to a height of the side panels **6006**.

30 35 40 As shown, the lid **6020** has flaps **6024**, **6026** that are connected to each other such that they do not move with respect to each other. Additionally, the end flap **6024** and/or the side flaps **6026** may not move relative to the top wall **6022**. Accordingly, when the lid **6020** is folded over and its 45 internal surfaces engage with the external surfaces of first end panel **6004a** and side panels **6006**, the lid **6020** acts as a panel-retaining structure that encloses and prevents outward collapse of first end panel **6004a** and side panels **6006**.

45 Alternatively, flaps **6024** and **6026** may be separated from each other such that they are movable with respect to each other. When the lid **6020** is folded over and its internal 50 surface engages with the external surfaces of the first end panel **6004a** and side panels **6006**, an additional retaining means such as a magnet may be disposed between the internal surfaces and the external surfaces such that the lid **6020** may act as a panel-retaining structure that encloses and prevents outward collapse of the first end panel **6004a** and side panels **6006**. This configuration allows the packaging to be substantially flattened when opened.

55 60 65 In some forms, respective pairs of panels **6004a**, **6004b**, **6006** may be joined by a foldable web **6010**. As shown in FIG. 4A, each foldable web **6010** may comprise a pair of substantially triangular portions **6012** joined at a fold **6014**. The webs **6010** are inwardly foldable about the fold **6014** as panels **6004a**, **6004b**, **6006** are inwardly folded, such that the substantially triangular portions **6012** are flattened against each other when the packaging **6000** is closed. By providing

webs **6010** between the panels, folding of the panels to form the housing for the patient interface **3000** is made easier.

In some forms, the inwardly folded webs **6010** may extend at least partially across the second panel portion **6036**, thereby reducing the internal volume of the packaging **6000**. This may be beneficial in creating less room for the patient interface to move within the packaging **6000**.

At least one panel of the packaging **6000** further comprises at least one patient interface retaining feature that is attachable to the patient interface **3000**. Various examples of such retaining features are shown in FIGS. 8A to 8G and will be described in further detail below. In some forms, each of the end panels and the side panels may comprise one or more patient interface retaining features.

For example, the second panel portion **6036** of the first end panel **6004a** may comprise one or more patient interface retaining features **8004a**, **8004b** (FIGS. 4C, 4D, 8G) arranged to attach to the patient interface **3000** at or near the plenum chamber **3200**. In some examples, the one or more patient interface retaining features are arranged to attach on either side of the plenum chamber **3200** (FIG. 4D). For example, attachment may be at the concertina portions **3322** of the patient interface **3000** (see e.g., FIGS. 3C and 3D) on either side, and/or near the connection points **3310** of the straps **3302** to the plenum chamber **3200**. As shown in FIGS. 4C and 4D, the patient interface retaining features **8004a** and **8004b** are configured to be engageable with each other in order to retain the patient interface **3000** within the package. In other words, the patient interface retaining features **8004a** and **8004b** do not mate with the patient interface **3000**.

Alternatively, the patient interface retaining features **8004a** and **8004b** may be engageable with itself in order to retain the patient interface **3000** within the package. Each retaining feature **8004a**, **8004b** may not mate with the patient interface **3000**. Instead, each retaining feature **8004a**, **8004b** may be wrapped around a portion of the patient interface **3000** and folded against itself.

Alternatively, the patient interface **3000** may comprise a complementary mating means for engaging with the patient interface retaining features **8004a**, **8004b**. The complementary mating means may be defined by the patient interface **3000**, or may be additional to the patient interface **3000**.

The one or more patient interface retaining features **8004a**, **8004b** preferably do not contact the seal-forming structure **3100**, for hygiene purposes.

In some forms, the one or more patient interface retaining features **8004a**, **8004b** are arranged on the first end panel **6004a** to provide a clearance between the patient interface **3000** and the panels **6004a**, **6006** when the patient interface **3000** is attached. For example, the one or more patient interface retaining features **8004a**, **8004b** may be arranged such that there is a sufficient clearance between the plenum chamber **3200** and the first panel portion **6034** to prevent transfer of any ink or other material from the internal surface of first panel portion **6034** to the plenum chamber **3200**.

The one or more patient interface retaining features **8004a**, **8004b** (FIGS. 4C, 4D, 8G) may be magnetic and arranged to loop over the patient interface **3000** at or near the plenum chamber **3200**. For example, retaining feature **8004a** may comprise a magnet and retaining feature **8004b** may comprise another magnet such that their unlike poles faces each other and configured for magnetic attraction. Retaining features **8004a** and **8004b** thus secures the patient interface **3000** within the loop formed when the magnets are attracted to each other. Alternatively, the magnetic patient interface retaining features may engage a complementary mating means on the patient interface **3000**. The complementary

mating means may be defined by the patient interface **3000**, or may be additional to the patient interface **3000**.

In some forms, the engageable nature of the patient interface retaining features **8004a**, **8004b** may allow them to mechanically connect to one another. This may be instead of or in addition to the magnetic connection described above. For example, magnetic attraction between the patient interface retaining features **8004a**, **8004b** may provide additional retention to better ensure that the patient interface retention features **8004a**, **8004b** stay connected to one another.

In certain forms, the patient interface retaining feature **8004a** may include a free end with a pair of arms **8005** configured to form a groove **8006**. The patient interface retaining feature **8004b** may include an overhang **8007** with a narrow portion proximate to the free end. The groove **8006** may be a female part that receives the narrow portion (e.g., a male part) so that the pair of arms **8005** wrap around the patient interface retaining feature **8004b** and selectively lock the two features together. The patient interface retaining feature **8004b** may be slightly rotated (e.g., bent, turned, flexed, etc.) relative to the patient interface retaining feature **8004a** in order to disengage the two features from one another.

In some forms, each of the side panels **6006** may comprise at least one patient interface retaining feature **8004a** arranged to attach to respective sides of the patient interface **3000**. For example, the at least one patient interface retaining structure may attach to the second tie **3306** at a point intermediate the connector **3307** and the third tie **3308**. In some forms, the at least one patient interface retaining feature **8004a** may attach to the second tie **3306** at a point at or near the connector **3307**. In some forms, one patient interface retaining feature **8004a** may attach to the second tie **3306** at a point at or near the connector **3307** and another patient interface retaining feature **8004a** may attach to the second tie **3306** at a point at or near the third tie **3308**. In some forms, the second tie **3306**, the connector **3307**, the third tie **3308**, and/or any point intermediate these entities may each independently comprise a magnet in order to correspondingly be attracted to a magnetic retaining feature **8004a** on each of the side panels **6006**.

In some forms, the first panel portion **6021** and/or the second panel portion **6022** of the second end panel **6004b** may comprise one or more patient interface retaining features arranged to attach to the patient interface **3000** at or near the third tie **3308**. In some examples, the one or more patient interface retaining features are arranged to attach on either side of the third tie **3308**. For example, attachment may be to the second tie **3306** on either side of the third tie **3308**. In some forms, the third tie **3308** or any point near the third tie **3308** may comprise a magnet in order to correspondingly be attracted to a magnetic retaining structure on the first panel portion **6021** and/or the second panel portion **6022**.

In some forms, the one or more patient interface retaining features are arranged on the second end panel **6004b** to provide a clearance between the patient interface **3000** and the second end panels **6004b** when the patient interface **3000** is attached. For example, the one or more patient interface retaining features **8004a**, **8004b** may be arranged such that there is a sufficient clearance between the third tie **3308** and second tie **3306**, and the end flap **6024**, such that when the lid **6020** is closed over the side panels **6006** and first end panel **6004a**, the second tie **3306** and third tie **3308** do not interfere with the closing.

In some forms, second panel portion **6036** may comprise at least one patient interface retaining feature **8004b**

arranged to attach to respective sides of the patient interface **3000**. For example, the at least one patient interface retaining structure may attach to the second tie **3306** at a point intermediate the connector **3307** and the third tie **3308**. In some forms, the at least one patient interface retaining structure may attach to the second tie **3306** at a point at or near the connector **3307**. In some forms, one patient interface retaining structure may attach to the second tie **3306** at a point at or near the connector **3307** and another patient interface retaining structure may attach to the second tie **3306** at a point at or near the third tie **3308**. In some forms, the second tie **3306**, the connector **3307**, the third tie **3308**, and/or any point intermediate these entities may each independently comprise a magnet in order to correspondingly be attracted to a magnetic retaining feature **8004b** on second panel portion **6036**.

In some forms, the packaging **6000** may be manufactured with the patient interface retaining features **8004a** and **8004b** substantially flush with the remainder of the surface of the respective panel. As illustrated in FIG. 4C, the patient interface retaining features **8004a** and **8004b** may be pulled away from the surface and leave a space **8009** in the surface that corresponds to the shape of the respective retaining feature **8004a**, **8004b**. The space **8009** may be a cut-out or depression in the surface of the respective panel in the shape of the respective retaining feature **8004a**, **8004b**.

In certain forms, an outer surface **8008** of the patient interface retaining features **8004a**, **8004b** and/or the surface of space **8009** formed in the surface of the respective panel may be backed with an adhesive or other connecting material (e.g., hook and loop material, a magnet, a mechanical fastener, etc.). For example, the outer surface **8008** and the space **8009** may face one another (see e.g., FIG. 8G). When the retaining feature **8004a** is decoupled from the retaining feature **8004b**, the retaining feature **8004a** may move toward the space **8009** in the layer **8002a** so that the connecting material can retain the retaining feature **8004a** relative to the respective panel. The same description may also be applicable for the retaining feature **8004b** relative to the space **8009** in the layer **8002b**. The use of the connecting material may allow the patient interface retaining features **8004a** and **8004b** to return to their substantially flush position when not in use (e.g., forming a more compact appearance). The connecting materials may also allow for repeated connection and disconnection between the outer surface **8008** and the space **8009** so that the retaining features **8004a**, **8004b** may be stored while not in use and connected to one another when in use.

In some forms, prior to the first use, the patient interface retaining features **8004a** and **8004b** may be outlined at least partially with perforations, which may indicate to the patient where the patient interface retaining features **8004a** and **8004b** are located.

In some forms, each patient interface retaining feature **8004a** may connect to a patient interface retaining structure **8004b** located on a separate panel of the packaging **6000**. The panels including the corresponding patient interface retaining features **8004a** and **8004b** may be adjacent to one another and separated by a fold.

In some forms (not shown), a single panel may include both of the patient interface retaining features **8004a**, **8004b**. In other words, the connecting pair of patient interface retaining features **8004a**, **8004b** may be included on the same panel instead of adjacent panels, as illustrated in FIG. 4C.

An opening sequence of the packaging **6000** is depicted in FIGS. 5A to 5C. As shown in FIG. 5A the user grips the

external surfaces of the lid **6020** of packaging **6000**, for example at the end flap **6024** and first panel portion **6021**.

Next, as shown in FIG. 5B, the lid **6020** is pulled away from the first end wall defined by first end panel portion **6034** of the first end panel **6004a**. The illustrated example shows the lid **6020** moved in the first direction **6035** (e.g., counter clockwise as illustrated). This movement of the lid **6020** releases the first end panel **6004a** to allow it to begin to collapse outwardly. In the illustrated example, the first end panel **6004a** moves in a second direction **6037** (e.g., clockwise as illustrated) that is generally opposite from the first direction **6035**. For example, the first end panel **6004a** may be biased toward a collapsed position (e.g., where the first end panel portion **6034** moves toward being co-planar or is co-planar with the second panel portion **6036**, like in FIG. 4B) and may move toward the collapsed position when no longer restrained by the lid **6020**. In the depicted example, as a clearance is provided between the patient interface **3000** and the first end panel portion **6034**, the patient interface **3000** does not apply any force to the first end panel portion **6034**, but it will be appreciated that in other examples, the patient interface **3000** may urge the first end panel portion **6034** outwardly to encourage the collapse.

In the intermediate position shown in FIG. 5B, the side flaps **6026** of the lid **6020** remain partially in contact with the side panels **6006**. When the lid **6020** is fully removed as shown in FIG. 5C, the side panels **6006** are released and may begin to collapse outwardly. The side panels **6006** may be biased toward a collapsed position (e.g., where the side panels **6006** move toward being co-planar or are co-planar with the second panel portion **6036**, like in FIG. 4B) and may move toward the collapsed position when no longer restrained by the lid **6020**. The collapse may also be aided by the weight of the straps **3302** and/or the first and second ties **3304**, **3306** of the patient interface **3000**, which may contact the internal surfaces of side panels **6006** to urge them outwardly. Where the straps **3302** comprise rigidizers **3316**, if the rigidizers **3316** are resilient along at least part of their length, they may be stored under tension in the packaging **6000** and spring outwardly to contact side panels **6006**. Further, when the lid **6020** is fully opened, the weight of the posterior part of the patient interface **3000** (including the third tie **3308** and portions of the first and second ties **3304**, **3306**) may act to urge the second end panel **6004b** outwardly to encourage it to collapse.

Accordingly, when the lid **6020** is fully opened and panels **6004a**, **6004b**, **6006** are fully released, the patient interface **3000** may be displayed in a configuration substantially corresponding to the manner in which it would be worn by a patient in use, as shown in FIG. 4B.

To further assist the patient, one or more internal surfaces of the packaging **6000** may carry printed indicia, which may comprise graphics and/or text that provide instructions for use of the patient interface **3000**.

Turning now to FIGS. 6A to 6D and 7A to 7D, another form of the packaging of the present technology is shown.

The packaging **7000** comprises a plurality of panels **7004a**, **7004b**, and **7006**. The plurality of panels is arranged to be folded inwardly to define a housing for the patient interface **3000**.

In this example, the plurality of panels comprises a first end panel **7004a** and a second end panel **7004b**, each joined to a bottom wall **7002** at a respective fold **7022a**, **7022b**. The plurality of panels also comprises a pair of opposed side panels **7006** that are joined to the bottom wall **7002** at folds **7020**.

The first end panel 7004a has a pair of side flaps 7008a extending from it. A top flap 7009a extends from the first end panel 7004a and spans between the side flaps 7008a. Together, the side flaps 7008a and top flap 7009a form a first lid portion 7010a extending from the first end panel 7004a.

In some forms, each side flap 7008a may be arranged substantially perpendicularly with respect to the first end panel 7004a. In some forms, the top flap 7009a may be arranged substantially perpendicularly with respect to the first end panel 7004a.

In certain forms, this position may remain regardless of whether the packaging 7000 is in the open position of the closed position.

Similarly, the second end panel 7004b has a pair of side flaps 7008b extending from it. A top flap 7009b extends from the second end panel 7004b and spans between the side flaps 7008b. Together, the side flaps 7008b and top flap 7009b form a second lid portion 7010b extending from the second end panel 7004b.

In some forms, each side flap 7008b may be arranged substantially perpendicularly with respect to the second end panel 7004b. In some forms, the top flap 7009b may be arranged substantially perpendicularly with respect to the second end panel 7004b.

In certain forms, this position may remain regardless of whether the packaging 7000 is in the open position or the closed position.

In use, the two lid portions 7010a, 7010b cooperate with end panels 7004a, 7004b and side panels 7006 to enclose the patient interface 3000. To do so, side panels 7006 are folded inwardly (towards the bottom wall 7002) about fold lines 7020 to a substantially upright position, and end panels 7004a and 7004b are then folded inwardly (towards the bottom wall 7002) such that the respective side flaps 7008a and 7008b pass over the side panels 7006 in their upright position, and the inner edges of top panels 7009a, 7009b overlap, meet or almost meet so that the top panels 7009a and 7009b together form a top wall covering a space defined by end panels 7004a and 7004b, and side panels 7006. The side flaps 7008a and 7008b act to prevent the side panels 7006 collapsing outwardly while the lid 7010a, 7010b is in place. A sleeve 7030 (FIG. 7B) may then be fitted over the end panels 7004a, 7004b to prevent them from collapsing outwardly. Accordingly, the lid 7010a, 7010b and sleeve 7030 act as panel-retaining structures that enclose and prevent outward collapse of first and second end panels 7004a, 7004b and side panels 7006.

At least one panel of the packaging 7000 further comprises at least one patient interface retaining feature that is attachable to the patient interface 3000.

For example, as best shown in FIG. 7D, the first end panel 7004a may comprise one or more patient interface retaining features 8014 arranged to attach to the patient interface 3000 at or near the plenum chamber 3200. In some examples, the one or more patient interface retaining features 8014 are arranged to attach on either side of the plenum chamber 3200. For example, attachment may be at the concertina portions 3322 on either side, and/or near the connection points 3310 of the straps 3302 to the plenum chamber 3200.

The one or more patient interface retaining features preferably do not contact the seal-forming structure 3100, for hygiene purposes.

In some forms, the one or more patient interface retaining features 8014 are arranged on the first end panel 7004a to provide a clearance between the patient interface 3000 and the side flaps 7008a when the patient interface 3000 is attached. For example, the one or more patient interface

retaining features 8014 may be arranged such that there is a sufficient clearance between the patient interface 3000 and the side flaps 7008a to enable the side panels 7006 to fit between the patient interface 3000 and the side flaps 7008a.

- 5 The one or more patient interface retaining features 8014 may be magnetic and arranged to loop over the patient interface 3000 at or near the plenum chamber 3200. In some examples, retaining feature 8014 comprises a magnet attractable to another magnet on first end panels 7004a.
- 10 Patient interface retaining features 8014 thus secures the patient interface 3000 within the loop formed when the magnets are attracted to each other.

In some forms, each of the side panels 7006 may comprise at least one patient interface retaining structure 8010 arranged to attach to respective sides of the patient interface 3000. For example, the at least one patient interface retaining structure 8010 may attach to the second tie 3306 at a point intermediate the connector 3307 and the plenum chamber 3200. In some forms, the at least one patient interface retaining structure 8010 may attach to the second tie 3306 at a point at or near the connector 3307. In some forms, one patient interface retaining structure 8010 may attach to the second tie 3306 at a point at or near the connector 3307 on one side of the connector 3307 and another patient interface retaining structure 8010 may attach to the second tie 3306 at a point at or near the connector 3307 on the other side of the connector 3307. In some forms, each of the side panels 7006 may comprise at least one magnetic patient interface retaining structure 8010 arranged to attach to respective sides of the patient interface 3000. The respective sides of the patient interface 3000 may comprise a magnet with unlike poles facing the magnetic patient interface retaining structure 8010. For example, the second tie 3306, the connector 3307, and/or any point intermediate these entities may each independently comprise a magnet in order to correspondingly be attracted to a magnetic retaining feature 8014 on each of the side panels 7006.

40 In some forms, the patient interface retaining structure 8010 may be formed from a separate material than the panels (e.g., the side panels 7006). The patient interface retaining structure 8010 may be connected (e.g., using an adhesive, stitching, mechanical connectors, etc.) to the panels. The patient interface retaining structure 8010 could be constructed from a textile, although other materials may also be used.

45 In some forms, the second end panel 7004b may comprise one or more patient interface retaining features 8012 arranged to attach to the patient interface 3000 at or near the third tie 3308. In some examples, the one or more patient interface retaining features 8012 are arranged to attach on either side of the third tie 3308. For example, attachment may be to the second tie 3306 on either side of the third tie 3308, as shown in FIG. 7D. In some forms, the second end panel 7004b may comprise at least one magnetic patient interface retaining feature 8012 arranged to attach to respective sides of the patient interface 3000. The respective sides of the patient interface 3000 may comprise a magnet with unlike poles facing the magnetic patient interface retaining feature 8012. For example, the third tie 3308 or any point intermediate the third tie 3308 may comprise a magnet in order to correspondingly be attracted to a magnetic retaining feature 8012 on the second end panel 7004b.

50 In some forms, the one or more patient interface retaining features 8012 are arranged on the second end panel 7004b to provide a clearance 7042 between the patient interface 3000 and the side flaps 7008b when the patient interface 3000 is

attached. For example, the one or more patient interface retaining features **8012** may be arranged such that there is a sufficient clearance **7042** between the patient interface **3000** and the side flaps **7008b**, such that when the lid portion **7010b** is closed over the side panels **7006**, the side panels **7006** may fit in the clearance region **7042** so that the patient interface **3000** does not interfere with the closing of the lid portion **7010b**.

An opening sequence of the packaging **7000** is depicted in FIGS. 7A to 7D. As shown in FIG. 7A the user grasps the sleeve **7030** of packaging **7000**, and as shown in FIG. 7B, starts to pull it away to begin to expose the lid portions **7010a**, **7010b**.

In some forms, the user may first apply a force to one of the side panels **7006** (or another panel depending on the orientation of the sleeve **7030**). This force is illustrated by the arrow **7100** in FIG. 7A. The force **7100** may create relative movement between the sleeve **7030** and the remainder of the packaging **7000**. In other words, the force **7100** may move the packaging toward the orientation of FIG. 7B where at least part of the lid portions **7010a**, **7010b** is exposed.

Once the lid portions **7010a**, **7010b** (or part thereof) are exposed, the user may continue to apply forces in order to separate the sleeve **7030** and fully expose the packaging **7000**. For example, the user may grasp the sleeve **7030** and pull in a direction **7104**. This direction **7104** may be oriented opposite the direction of force **7100** in order to further expose the lid portions **7010a**, **7010b**. Additionally, the user may pull the packaging **7000** in a direction **7108**, which may be opposite to the direction **7104**. Pulling the sleeve **7030** and packaging **7000** separately and in opposite direction may assist in fully exposing the lid portions **7010a**, **7010b**.

Next, as shown in FIG. 7C, the sleeve **7030** is completely removed from the packaging **7000**. This releases the lid portions **7010a**, **7010b**, and thus the end panels **7004a** and **7004b** to which they are attached, to allow them to collapse outwardly. For example, the lid portions **7010a**, **7010b** may move in opposite direction while moving toward the open position. As illustrated, lid portion **7010a** may move in a generally counter-clockwise direction "A" and the lid portion **7010b** may move in a generally clockwise direction "B". The weight of the components of the patient interface **3000** that are attached to the respective end panels **7004a** and **7004b** tends to urge the end panels **7004a**, **7004b** outwardly (away from the bottom wall **7002**) to encourage the collapse.

Finally, as shown in FIG. 7D, after the end panels **7004a**, **7004b** collapse and the side flaps **7008a**, **7008b** are clear of the side panels **7006**, the side panels **7006** also collapse under the weight of the straps **3302** and/or the first and second ties **3304**, **3306** to which the side panels **7006** are attached. The collapse may be aided by rigidizers **3316**, since as before, if the rigidizers **3316** are resilient along at least part of their length, they may be stored under tension in the packaging **6000** and spring outwardly to contact side panels **7006**.

Accordingly, when the lid **7010a**, **7010b** is fully opened and panels **7004a**, **7004b**, **7006** are fully released, the patient interface **3000** may be displayed in a configuration substantially corresponding to the manner in which it would be worn by a patient in use, as shown in FIG. 4B.

Several non-limiting examples of patient interface retaining structures are shown in FIGS. 8A to 8G.

In the examples of FIGS. 8A, 8F, and 8G, a patient interface retaining structure **8004** may comprise a strip or band of material, such as cardboard, that is looped over part

of the patient interface and secured to itself, or to another part of the packaging, such as a bottom wall of the packaging or to a layer of material **8002** that is attached to the bottom wall. The strip or band may be secured by any suitable means, such as adhesive, tape, and the like.

For example, in FIG. 8A, each of the opposed ends of a strip of material **8004** may be inserted into a hole in the layer **8002**. In another example shown in FIG. 8F, one end of strap **8004** may be affixed to a surface of the layer **8002**, and the other (free) end may be inserted into a hole **8003** in the layer **8002**.

In some examples, as shown in FIG. 8G, the strip of material may be a cut-out portion of, or otherwise extend from, the layer **8002** (e.g., this may be similar to the illustration of FIG. 4C). For example, a strip **8004a** that is cut out from region **8002a** may be looped over a part of the patient interface **3000** and then secured to a surface of the layer **8002**. In other examples, a strip **8004a** cut out from region **8002a** may connect with a second strip **8004b** cut out from another region **8002b** of the layer **8002**. In some forms, a head portion of the first strip **8004a** may have a shape that complements a head portion of the second strip **8004b** so that the head portions interlock to secure the patient interface **3000** to the packaging.

An arrangement such as that shown in FIGS. 8A, 8F, and 8G may be useful where the packaging is designed to be disposable and is preferred to be recyclable.

In the example of FIG. 8B, the patient interface retaining feature **8012** comprises a fabric or ribbon **8020** that is wrapped around a button **8022**. One end of the ribbon **8020** may be secured to the packaging (for example, end panel **7004b**), and the button **8022** may also be secured to the packaging, such that the other end of the ribbon may be wrapped around it.

In the example of FIG. 8C, the patient interface retaining feature **8014** comprises an elastic band **8030** that has an aperture at a free end to receive a button **8032**. The elastic band **8030** may be constructed from any material that provides resilient extensibility. One end of the elastic band **8030** may be secured to the packaging (for example, end panel **7004a**), and the button **8032** may also be secured to the packaging, such that the free end of the elastic band **8030** may be secured to the button **8032**. In this example, the button **8032** may be considered a male part that is selectively receivable in an opening of the elastic band **8030** (e.g., the female part).

In the example of FIG. 8D and FIG. 8E, the patient interface retaining structure **8010** comprises an elastic band that has a first end **8040** that is secured to the packaging, such as to the side panel **7006**, and a second, free, end **8042** that carries a male part **8044** of a press stud. A female part **8046** of the press stud is secured to the packaging, such that the free end **8042** of the elastic band may be stretched over part of the patient interface and the male part **8044** may be pressed into the female part **8046** to secure the patient interface. It will be appreciated that male and female parts may be switched.

As mentioned above, the patient interface retaining feature may be magnetic. The magnetic patient interface retaining feature may have a first end that is secured to the packaging, and a second, free, end that carries a magnet. The magnetic patient interface retaining feature be attracted to another magnetic patient interface retaining feature having opposite poles in order to secure the patient interface within the loop that is formed. Alternatively, the magnetic patient interface retaining feature may be attracted to another magnet on the first, second and/or side panels of the packaging

in order to secure the patient interface within the loop that is formed. Alternatively, the magnetic patient interface retaining feature may be attracted to another magnet on the patient interface in order to secure the patient interface.

For example, the male and female parts **8044**, **8046** in FIG. 8D may connect to one another using a magnetic attraction instead of and/or in addition to the mechanical interaction described above.

It was found that the retaining features (and especially the magnetic retaining features) better secure the patient interface in the packaging so that squeezing of the patient interface may be avoided. The retaining features act as holding features in the packaging, so that the patient interface is presented in a fixed position when the packaging is opened. This may additionally be paired with instructions in the packaging to help first time users understand how to wear the patient interface. If the patient interface has some rigidity, the retaining features may further facilitate the display of the patient interface when the packaging is opened.

Any combination of the patient interface retaining features in FIGS. 8A to 8G and the magnetic patient interface retaining features may be used with packaging **6000** or packaging **7000**.

A further form of the packaging will now be described with reference to FIGS. 9A-9D. As best shown in the open view of FIG. 9C, packaging **9000** comprises a plurality of panels **9004a**, **9004b**, **9006**. The plurality of panels is arranged to be folded inwardly to define a housing for a patient interface **3000** (FIG. 9B).

In this example, the plurality of panels comprises a first end panel **9004a** and a second end panel **9004b** opposite the first end panel **9004a**. The first and second end panels **9004a**, **9004b** are each connected to a bottom panel **9002** that defines a bottom wall of the packaging. Each of the first and second end panels **9004a**, **9004b** is inwardly foldable (i.e. towards bottom panel **9002**) to a generally upright position to form respective end walls of a housing for the patient interface **3000**.

The plurality of panels also comprises a top panel **9010** extending from the second end panel **9004b**. The top panel **9010** is inwardly foldable to form a lid for the packaging **9000**.

The plurality of panels further comprises a pair of opposed side panels **9006**. Each side panel **9006** is inwardly foldable (i.e., towards bottom panel **9002**) to a generally upright position to form a side wall of the housing for the patient interface **3000**.

The top panel **9010** comprises one or more panel retaining structures for preventing outward collapse of the side panels **9006** and first end panel **9004a**. For example, the top panel **9010** may comprise an end flap **9024** extending generally perpendicular to the top panel **9010**. The end flap **9024** may engage with an external surface of the first end panel **9004a**. The end flap **9024** acts as a panel-retaining structure to prevent outward collapse of the first end panel **9004a**.

The top panel **9010** may also comprise a pair of opposed side flaps **9026** that extend mutually perpendicularly to the top panel **9010** and the end flap **9024**. The side flaps **9026** may be connected to both the top panel **9010** and the end flap **9024**. Accordingly, when side panels **9006**, first end panel **9004a** and second end panel **9004b** are all folded inwardly, each side flap **9026** of the top panel **9010** may be arranged to engage with respective external surfaces of the side panels **9006** in their upright position, and thus act as part of a panel-retaining structure that also comprises the end flap **9024**.

In some forms, the top panel **9010** may comprise one or more magnetic connectors that releasably fasten the top panel **9010** to the side panels **9006** and first end panel **9004a**. For example, first end panel **9004a** and side panels **9006** may each comprise first magnetic portions (e.g. located at a flattened top portion of the first end panel **9004a** and side panels **9006**) that magnetically attach to corresponding second magnetic portions on the top panel **9010**.

At least one panel of the packaging **9000** further comprises at least one patient interface retaining feature (as mentioned above) that is attachable to the patient interface **3000**. For example, a hook **9030** or other member (such as a clip, catch, or hook-and-loop fastener) suitable for attachment to an upper portion of the patient interface, such as at a position along crown strap **3303**, may be provided on a lower surface of the top panel **9010**.

In some forms, the hook **9030** may be constructed from a different material than the top panel **9010**. For example, the hook **9030** may be constructed from a more rigid material than the top panel **9010**.

As illustrated in FIG. 9D, the hook **9030** may be positioned on an interior surface of the top panel **9010**. The hook **9030** may hang directly over the bottom panel **9002**.

In some forms, the hook **9030** may have a substantially angular shape. For example, FIG. 9D illustrates that the hook **9030** includes a plurality of segments that are formed at angles with respect to one another. These angles may be right angles, although other angles are also contemplated.

In other forms, the hook **9030** may be at least partially smooth. For example, the hook **9030** may be at least partially curved between its free end and fixed end.

In some forms, at least one of the side panels **9006**, first end panel **9004a** and second end panel **9004b** may also comprise a patient interface retaining feature, such as any of the features shown in FIGS. 8A to 8G.

The top panel **9010** may further comprise a tab or other grippable member **9020** projecting from its external surface to enable a user to pick up the packaging without holding the sides of the packaging **9000**. In some forms of the present technology, this causes the one or more panel-retaining structures to release due to the weight of the patient interface **3000**, to thereby cause the side panels **9006** and first end panel **9004a** to collapse.

In some forms, the top panel **9010** may be hinged at an intermediate section thereof to define a first top panel portion **9010a** and a second top panel portion **9010b** such that picking up the packaging **9000** by the tab **9020** causes the top panel **9010** to collapse outwardly (away from bottom panel **9002**) as the panels **9006** and **9004a** are released from the top panel **9010** under the weight of the patient interface **3000**.

The packaging **6000**, **7000**, **9000** may be partially or completely formed from cardboard. In some examples, the packaging may be formed from two or more layers of cardboard of different types. For example, an outer layer of the packaging may be 300 gsm solid fibreboard and an inner layer may be corrugated E flute cardboard having a thickness of 1.5 mm.

5.5 RPT DEVICE

An RPT device **4000** in accordance with one aspect of the present technology comprises mechanical, pneumatic, and/or electrical components and is configured to execute one or more algorithms, such as any of the methods, in whole or in part, described herein. The RPT device **4000** may be configured to generate a flow of air for delivery to a patient's

airways, such as to treat one or more of the respiratory conditions described elsewhere in the present document.

5.6 AIR CIRCUIT

An air circuit **4170** in accordance with an aspect of the present technology is a conduit or a tube constructed and arranged to allow, in use, a flow of air to travel between two components such as RPT device **4000** and the patient interface **3000**.

5.7 HUMIDIFIER

5.7.1 Humidifier Overview

In one form of the present technology there is provided a humidifier **5000** to change the absolute humidity of air or gas for delivery to a patient relative to ambient air. Typically, the humidifier **5000** is used to increase the absolute humidity and increase the temperature of the flow of air (relative to ambient air) before delivery to the patient's airways.

5.8 GLOSSARY

For the purposes of the present technology disclosure, in certain forms of the present technology, one or more of the following definitions may apply. In other forms of the present technology, alternative definitions may apply.

5.8.1 General

Air: In certain forms of the present technology, air may be taken to mean atmospheric air, and in other forms of the present technology air may be taken to mean some other combination of breathable gases, e.g. oxygen enriched air.

Ambient: In certain forms of the present technology, the term ambient will be taken to mean (i) external of the treatment system or patient, and (ii) immediately surrounding the treatment system or patient.

For example, ambient humidity with respect to a humidifier may be the humidity of air immediately surrounding the humidifier, e.g. the humidity in the room where a patient is sleeping. Such ambient humidity may be different to the humidity outside the room where a patient is sleeping.

In another example, ambient pressure may be the pressure immediately surrounding or external to the body.

In certain forms, ambient (e.g., acoustic) noise may be considered to be the background noise level in the room where a patient is located, other than for example, noise generated by an RPT device or emanating from a mask or patient interface. Ambient noise may be generated by sources outside the room.

Automatic Positive Airway Pressure (APAP) therapy: CPAP therapy in which the treatment pressure is automatically adjustable, e.g. from breath to breath, between minimum and maximum limits, depending on the presence or absence of indications of SDB events.

Continuous Positive Airway Pressure (CPAP) therapy: Respiratory pressure therapy in which the treatment pressure is approximately constant through a respiratory cycle of a patient. In some forms, the pressure at the entrance to the airways will be slightly higher during exhalation, and slightly lower during inhalation. In some forms, the pressure will vary between different respiratory cycles of the patient, for example, being increased in response to detection of indications of partial upper airway obstruction, and decreased in the absence of indications of partial upper airway obstruction.

Flow rate: The volume (or mass) of air delivered per unit time. Flow rate may refer to an instantaneous quantity. In

some cases, a reference to flow rate will be a reference to a scalar quantity, namely a quantity having magnitude only. In other cases, a reference to flow rate will be a reference to a vector quantity, namely a quantity having both magnitude and direction. Flow rate may be given the symbol Q . 'Flow rate' is sometimes shortened to simply 'flow' or 'airflow'.

In the example of patient respiration, a flow rate may be nominally positive for the inspiratory portion of a breathing cycle of a patient, and hence negative for the expiratory portion of the breathing cycle of a patient. Device flow rate, Q_d , is the flow rate of air leaving the RPT device. Total flow rate, Q_t , is the flow rate of air and any supplementary gas reaching the patient interface via the air circuit. Vent flow rate, Q_v , is the flow rate of air leaving a vent to allow washout of exhaled gases. Leak flow rate, Q_l , is the flow rate of leak from a patient interface system or elsewhere. Respiratory flow rate, Q_r , is the flow rate of air that is received into the patient's respiratory system.

Flow therapy: Respiratory therapy comprising the delivery of a flow of air to an entrance to the airways at a controlled flow rate referred to as the treatment flow rate that is typically positive throughout the patient's breathing cycle.

Humidifier: The word humidifier will be taken to mean a humidifying apparatus constructed and arranged, or configured with a physical structure to be capable of providing a therapeutically beneficial amount of water (H_2O) vapour to a flow of air to ameliorate a medical respiratory condition of a patient.

Leak: The word leak will be taken to be an unintended flow of air. In one example, leak may occur as the result of an incomplete seal between a mask and a patient's face. In another example leak may occur in a swivel elbow to the ambient.

Noise, conducted (acoustic): Conducted noise in the present document refers to noise which is carried to the patient by the pneumatic path, such as the air circuit and the patient interface as well as the air therein. In one form, conducted noise may be quantified by measuring sound pressure levels at the end of an air circuit.

Noise, radiated (acoustic): Radiated noise in the present document refers to noise which is carried to the patient by the ambient air. In one form, radiated noise may be quantified by measuring sound power/pressure levels of the object in question according to ISO 3744.

Noise, vent (acoustic): Vent noise in the present document refers to noise which is generated by the flow of air through any vents such as vent holes of the patient interface.

Oxygen enriched air: Air with a concentration of oxygen greater than that of atmospheric air (21%), for example at least about 50% oxygen, at least about 60% oxygen, at least about 70% oxygen, at least about 80% oxygen, at least about 90% oxygen, at least about 95% oxygen, at least about 98% oxygen, or at least about 99% oxygen. "Oxygen enriched air" is sometimes shortened to "oxygen".

Medical Oxygen: Medical oxygen is defined as oxygen enriched air with an oxygen concentration of 80% or greater.

Patient: A person, whether or not they are suffering from a respiratory condition.

Pressure: Force per unit area. Pressure may be expressed in a range of units, including cmH_2O , $g-f/cm^2$ and hectopascal. 1 cmH_2O is equal to 1 $g-f/cm^2$ and is approximately 0.98 hectopascal (1 hectopascal=100 Pa=100 N/m^2 =1 milibar~0.001 atm). In this specification, unless otherwise stated, pressure is given in units of cmH_2O .

The pressure in the patient interface is given the symbol P_m , while the treatment pressure, which represents a target

value to be achieved by the interface pressure P_m at the current instant of time, is given the symbol P_t .

Respiratory Pressure Therapy: The application of a supply of air to an entrance to the airways at a treatment pressure that is typically positive with respect to atmosphere.

Ventilator: A mechanical device that provides pressure support to a patient to perform some or all of the work of breathing.

5.8.1.1 Materials

Silicone or Silicone Elastomer: A synthetic rubber. In this specification, a reference to silicone is a reference to liquid silicone rubber (LSR) or a compression moulded silicone rubber (CMSR). One form of commercially available LSR is SILASTIC (included in the range of products sold under this trademark), manufactured by Dow Corning. Another manufacturer of LSR is Wacker. Unless otherwise specified to the contrary, an exemplary form of LSR has a Shore A (or Type A) indentation hardness in the range of about 35 to about 45 as measured using ASTM D2240

Polycarbonate: a thermoplastic polymer of Bisphenol-A Carbonate.

5.8.1.2 Mechanical Properties

Resilience: Ability of a material to absorb energy when deformed elastically and to release the energy upon unloading.

Resilient: Will release substantially all of the energy when unloaded. Includes e.g. certain silicones, and thermoplastic elastomers.

Hardness: The ability of a material *per se* to resist deformation (e.g. described by a Young's Modulus, or an indentation hardness scale measured on a standardised sample size).

'Soft' materials may include silicone or thermo-plastic elastomer (TPE), and may, e.g. readily deform under finger pressure.

'Hard' materials may include polycarbonate, polypropylene, steel or aluminium, and may not e.g. readily deform under finger pressure.

Stiffness (or rigidity) of a structure or component: The ability of the structure or component to resist deformation in response to an applied load. The load may be a force or a moment, e.g. compression, tension, bending or torsion. The structure or component may offer different resistances in different directions. The inverse of stiffness is flexibility.

Floppy structure or component: A structure or component that will change shape, e.g. bend, when caused to support its own weight, within a relatively short period of time such as 1 second.

Rigid structure or component: A structure or component that will not substantially change shape when subject to the loads typically encountered in use. An example of such a use may be setting up and maintaining a patient interface in sealing relationship with an entrance to a patient's airways, e.g. at a load of approximately 20 to 30 cmH₂O pressure.

As an example, an I-beam may comprise a different bending stiffness (resistance to a bending load) in a first direction in comparison to a second, orthogonal direction. In another example, a structure or component may be floppy in a first direction and rigid in a second direction.

5.8.2 Patient Interface

Anti-asphyxia valve (AAV): The component or sub-assembly of a mask system that, by opening to atmosphere in a failsafe manner, reduces the risk of excessive CO₂ rebreathing by a patient.

Elbow: An elbow is an example of a structure that directs an axis of flow of air travelling therethrough to change direction through an angle. In one form, the angle may be

approximately 90 degrees. In another form, the angle may be more, or less than 90 degrees. The elbow may have an approximately circular cross-section. In another form the elbow may have an oval or a rectangular cross-section. In certain forms an elbow may be rotatable with respect to a mating component, e.g. about 360 degrees. In certain forms an elbow may be removable from a mating component, e.g. via a snap connection. In certain forms, an elbow may be assembled to a mating component via a one-time snap during manufacture, but not removable by a patient.

Frame: Frame will be taken to mean a mask structure that bears the load of tension between two or more points of connection with a headgear. A mask frame may be a non-airtight load bearing structure in the mask. However, some forms of mask frame may also be air-tight.

Headgear: Headgear will be taken to mean a form of positioning and stabilizing structure designed for use on a head. For example the headgear may comprise a collection of one or more struts, ties and stiffeners configured to locate and retain a patient interface in position on a patient's face for delivery of respiratory therapy. Some ties are formed of a soft, flexible, elastic material such as a laminated composite of foam and fabric.

Membrane: Membrane will be taken to mean a typically thin element that has, preferably, substantially no resistance to bending, but has resistance to being stretched.

Plenum chamber: a mask plenum chamber will be taken to mean a portion of a patient interface having walls at least partially enclosing a volume of space, the volume having air therein pressurised above atmospheric pressure in use. A shell may form part of the walls of a mask plenum chamber.

Seal: May be a noun form ("a seal") which refers to a structure, or a verb form ("to seal") which refers to the effect. Two elements may be constructed and/or arranged to 'seal' or to effect 'sealing' therebetween without requiring a separate 'seal' element *per se*.

Shell: A shell will be taken to mean a curved, relatively thin structure having bending, tensile and compressive stiffness. For example, a curved structural wall of a mask may be a shell. In some forms, a shell may be faceted. In some forms a shell may be airtight. In some forms a shell may not be airtight.

Stiffener: A stiffener will be taken to mean a structural component designed to increase the bending resistance of another component in at least one direction.

Strut: A strut will be taken to be a structural component designed to increase the compression resistance of another component in at least one direction.

Swivel (noun): A subassembly of components configured to rotate about a common axis, preferably independently, preferably under low torque. In one form, the swivel may be constructed to rotate through an angle of at least 360 degrees. In another form, the swivel may be constructed to rotate through an angle less than 360 degrees. When used in the context of an air delivery conduit, the sub-assembly of components preferably comprises a matched pair of cylindrical conduits. There may be little or no leak flow of air from the swivel in use.

Tie (noun): A structure designed to resist tension.

Vent: (noun): A structure that allows a flow of air from an interior of the mask, or conduit, to ambient air for clinically effective washout of exhaled gases. For example, a clinically effective washout may involve a flow rate of about 10 litres per minute to about 100 litres per minute, depending on the mask design and treatment pressure.

5.9 OTHER REMARKS

A portion of the disclosure of this patent document contains material which is subject to copyright protection.

The copyright owner has no objection to the facsimile reproduction by anyone of the patent document or the patent disclosure, as it appears in Patent Office patent files or records, but otherwise reserves all copyright rights whatsoever.

Unless the context clearly dictates otherwise and where a range of values is provided, it is understood that each intervening value, to the tenth of the unit of the lower limit, between the upper and lower limit of that range, and any other stated or intervening value in that stated range is encompassed within the technology. The upper and lower limits of these intervening ranges, which may be independently included in the intervening ranges, are also encompassed within the technology, subject to any specifically excluded limit in the stated range. Where the stated range includes one or both of the limits, ranges excluding either or both of those included limits are also included in the technology.

Furthermore, where a value or values are stated herein as being implemented as part of the technology, it is understood that such values may be approximated, unless otherwise stated, and such values may be utilized to any suitable significant digit to the extent that a practical technical implementation may permit or require it.

Unless defined otherwise, all technical and scientific terms used herein have the same meaning as commonly understood by one of ordinary skill in the art to which this technology belongs. Although any methods and materials similar or equivalent to those described herein may also be used in the practice or testing of the present technology, a limited number of the exemplary methods and materials are described herein.

When a particular material is identified as being used to construct a component, obvious alternative materials with similar properties may be used as a substitute. Furthermore, unless specified to the contrary, any and all components herein described are understood to be capable of being manufactured and, as such, may be manufactured together or separately.

It must be noted that as used herein and in the appended claims, the singular forms "a", "an", and "the" include their plural equivalents, unless the context clearly dictates otherwise.

All publications mentioned herein are incorporated herein by reference in their entirety to disclose and describe the methods and/or materials which are the subject of those publications. The publications discussed herein are provided solely for their disclosure prior to the filing date of the present application. Nothing herein is to be construed as an admission that the present technology is not entitled to antedate such publication by virtue of prior invention. Further, the dates of publication provided may be different from the actual publication dates, which may need to be independently confirmed.

The terms "comprises" and "comprising" should be interpreted as referring to elements, components, or steps in a non-exclusive manner, indicating that the referenced elements, components, or steps may be present, or utilized, or combined with other elements, components, or steps that are not expressly referenced.

The subject headings used in the detailed description are included only for the ease of reference of the reader and should not be used to limit the subject matter found throughout the disclosure or the claims. The subject headings should not be used in construing the scope of the claims or the claim limitations.

Although the technology herein has been described with reference to particular examples, it is to be understood that these examples are merely illustrative of the principles and applications of the technology. In some instances, the terminology and symbols may imply specific details that are not required to practice the technology. For example, although the terms "first" and "second" may be used, unless otherwise specified, they are not intended to indicate any order but may be utilised to distinguish between distinct elements. Furthermore, although process steps in the methodologies may be described or illustrated in an order, such an ordering is not required. Those skilled in the art will recognize that such ordering may be modified and/or aspects thereof may be conducted concurrently or even synchronously.

It is therefore to be understood that numerous modifications may be made to the illustrative examples and that other arrangements may be devised without departing from the spirit and scope of the technology.

20 The invention claimed is:

1. Packaging for a patient interface comprising a seal-forming structure with at least a nasal region, wherein the seal forming structure is coupled to a positioning and 25 stabilising structure with at least a first tie for holding the seal-forming structure in a therapeutically effective position on a patient's head, the packaging comprising:

a plurality of panels arranged to be folded inwardly to define a housing for the patient interface, the plurality of panels comprising a pair of opposed side panels and a pair of opposed end panels; and

a panel retainer that is configured to prevent outward collapse of the panels whilst the patient interface is held in a compressed state;

wherein at least one of the panels comprises at least one patient interface retainer configured to removably attach to the patient interface; and

wherein the panel retainer is configured to be released in order to cause the one or more panels to collapse outwardly and to allow the patient interface in the compressed state to urge one or more of the panels to collapse outwardly, to thereby enable display of the patient interface in a substantially in-use configuration.

2. Packaging according to claim 1, wherein the panel 45 retainer comprises a lid having at least one flap arranged to engage an external surface of a first end panel of the pair of opposed end panels.

3. Packaging according to claim 2, wherein the lid at least one of, extends from, and comprises at least part of, a second end panel of the pair of opposed end panels.

4. Packaging according to claim 3, wherein the lid has a hinge that is connected to, or is part of, the second end panel.

5. Packaging according to claim 4, wherein part of the second end panel forms a top wall of the lid.

6. Packaging according to claim 2, wherein the lid comprises first and second lid portions each comprising a pair of opposed side flaps arranged to engage with respective side panels; and wherein the panel retainer comprises the opposed side flaps of the first and second lid portions.

7. Packaging according to claim 6, wherein each lid portion comprises a top wall extending transversely of its opposed side flaps and a respective one of the end panels.

8. Packaging according to claim 6, wherein the panel retainer comprises a sleeve arranged to fit over the first and second lid portions.

9. Packaging according to claim 1, wherein the panels are joined by a foldable web.

31

10. Packaging according to claim 1, wherein the at least one patient interface retainer comprises one or more of: a tie; a clip; a press stud; a strap; a hook and loop fastener; a button; and a magnet.

11. Packaging according to claim 10, wherein the at least one patient interface retainer comprises a strap, and wherein the strap is formed from a cut-out portion of a layer of material that is laminated to one of the panels.

12. Packaging according to claim 10, wherein when the at least one patient interface retainer comprises a magnet, one of the end panels comprises at least two patient interface retainers arranged to be magnetically attractable to each other.

13. Packaging according to claim 10, wherein the at least one patient interface retainer comprises a magnet for attracting to a magnet on the patient interface.

14. Packaging according to claim 1, wherein the plurality of panels further comprises a top panel extending from one of said end panels, the top panel being arranged to fold to close the packaging.

15. Packaging according to claim 14, wherein the top panel comprises the panel retainer.

16. Packaging according to claim 14, wherein the top panel comprises one or more patient interface retainers arranged to attach to the patient interface at a crown region of the positioning and stabilising structure.

17. Packaging according to claim 16, wherein the one or more patient interface retainers of the top panel comprise one or more hooks.

18. Packaging according to claim 17, wherein on release of the panel retainer, the side panels and the other of said end panels is collapsible under gravity to display the patient interface in a hanging position.

19. Packaging according to claim 1, wherein one or more internal surfaces of the panels carries printed indicia.

20. Packaging according to claim 19, wherein the printed indicia comprise instructions for use of the patient interface.

21. A packaging system comprising:
a patient interface; and
the packaging of claim 1.

22. Packaging for a patient interface comprising a seal-forming structure with at least a nasal region, wherein the seal forming structure is coupled to a positioning and stabilising structure with at least a first tie for holding the seal-forming structure in a therapeutically effective position on a patient's head, the packaging comprising:

32

a plurality of panels arranged to be folded inwardly to define a housing for the patient interface, the plurality of panels comprising a pair of opposed side panels and a pair of opposed end panels; and

a panel retainer that is arranged to prevent outward collapse of the panels such that the patient interface is held in a compressed state;

wherein at least one of the panels comprises at least one patient interface retainer configured to removably attach to the patient interface; and

wherein the panel retainer is releasable to cause the patient interface in the compressed state to urge one or more of the panels outwardly, to thereby enable display of the patient interface in a substantially in-use configuration, and

wherein one of the end panels comprises at least two patient interface retainers arranged to attach to the patient interface on either side of the seal-forming structure, or at opposed ends of a posterior strap of the positioning and stabilising structure.

23. Packaging for a patient interface comprising a seal-forming structure with at least a nasal region, wherein the seal forming structure is coupled to a positioning and stabilising structure with at least a first tie for holding the seal-forming structure in a therapeutically effective position on a patient's head, the packaging comprising:

a plurality of panels arranged to be folded inwardly to define a housing for the patient interface, the plurality of panels comprising a pair of opposed side panels and a pair of opposed end panels; and

a panel retainer that is arranged to prevent outward collapse of the panels such that the patient interface is held in a compressed state;

wherein at least one of the panels comprises at least one patient interface retainer configured to removably attach to the patient interface; and

wherein the panel retainer is releasable to cause the patient interface in the compressed state to urge one or more of the panels outwardly, to thereby enable display of the patient interface in a substantially in-use configuration, and

wherein each end panel comprises at least one patient interface retainer, and each patient interface retainer of the end panels is positioned to provide a clearance to accommodate the side panels when the panels are folded inwardly.
